UNITED STATES PATENT OFFICE.

WILLIAM H. VIDOR, OF MAPLEWOOD, NEW JERSEY.

DESIGN FOR A LOUD SPEAKER FOR WIRELESS TELEPHONY.

Application filed January 8, 1924. Serial No. 8,277. Term of patent 8½ years.

To all whom it may concern:

Be it known that I, WILLIAM H. VIDOR, a citizen of Austria, residing at Maplewood, in the county of Essex and State of New Jersey, have invented a new, original, and ornamental Design for a Loud Speaker for Wireless Telephony, of which the following is a specification, reference being had to the accompanying drawings, forming a part thereof.

In said drawings, Figure 1 is a front

elevation of the loud speaker for wireless telephony; and Figure 2 is a side elevation of the same; said views illustrating the novel ornamental design.

I claim:—

The ornamental design for a loud speaker for wireless telephony, as shown.

WILLIAM H. VIDOR.
